DESIGN.

W. T. GOUGH.

CARPET.

No. 17,764.

Patented Oct. 11, 1887.

UNITED STATES PATENT OFFICE.

WILLIAM T. GOUGH, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 17,764, dated October 11, 1887.

Application filed August 30, 1887. Serial No. 248,313. Term of patent 3½ years.

To all whom it may concern:

Be it known that I, WILLIAM T. GOUGH, of Yonkers, county of Westchester, and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design is adapted for the border of a stair-carpet. It has a narrow inner margin of

an ornamental character. Next to this is a double row of small gem-shaped flowers. Above this is a line of large circular leaves, 20 in the angular spaces between which are line ornaments below and star-shaped flowers above. Over each of the large leaves is a smaller leaf of the same character, and above each of the star shaped flowers is a less prominent flower form of similar outline. 25

What I claim as new, and desire to secure by Letters Patent, is—

The design for a carpet-border, consisting of the design substantially as shown.

WM. T. GOUGH.
